COLLAPSIBLE BALLOT RECEPTACLE

Russel R. Miller, Silver Spring, Md.

Application September 1, 1950, Serial No. 182,698

3 Claims. (Cl. 232—2)

(Granted under Title 35, U. S. Code (1952),
sec. 266)

1

The invention described herein may be manufactured and used by or for the Government of the United States for governmental purposes without the payment to me of any royalty thereon in accordance with the provisions of the act of April 30, 1928 (Ch. 460, 45 Stat. L. 467).

My invention relates to a collapsible ballot receptacle comprising a supporting frame and a collapsible pouch which may be readily transported and when not in use may be collapsed into a compact unit for storage and/or shipment.

A further object of the invention is to provide a means for sealing the "ballot-box" after the polls have been officially closed. This sealing means is designed to give positive evidence of any tampering with the contents of the "box."

In the accompanying drawings which illustrate a preferred form of my invention:

Figure 1 is a top plan view of the device with supporting members in folded and locked position, and a seal in place with a signature applied.

Figure 2 is a side elevation of Figure 1 except for the omission of the seal.

Figure 3 is a cross-section on the line 3—3 of Figure 1, the seal being omitted.

Figure 4 is a side elevation of my device in operative position, with supporting members hooked over a portion of a supporting desk drawer or the like, the latter being indicated by dash and dot lines.

Figure 5 is a section on the line 5—5 of Figure 4 except that a hinged cover is in closed position.

Figure 6 is a side elevation of a portion of my device, showing the sealing means.

Figure 7 is a broken away detail showing one corner of a pouch frame and a supporting slide.

In these drawings:

A flexible pouch 10, which may be made of suitable canvas with concealed inturned seams to insure against any fraudulent tampering with the contents of a sealed box, has a margin 11 secured between two relatively rigid frames 12 which may be formed of fiber board or the like and united with the pouch by means of a suitable adhesive, staples, by sewing or by other suitable means. (See Figures 3, 5 and 7.)

The frames 12 fit in a recess 13 in a supporting slide 14 (Figure 7) which is provided with a central aperture 15 for receiving the pouch 10.

The supporting slide 14 is mounted in a groove 16 (Figure 3) in a main suspending closure member 17 (Figure 1) comprising an upper frame member 18 including a transverse bar 19, a closing sheet 20 provided with a narrow ballot receiving slot 21 (Figure 3), a U-shaped slide sup-

2

port 22 (Figure 3) for supporting the slide 14. The latter is free to be reciprocated in a groove formed by the closing sheet 20 and the U-shaped slide support 22 in combination with an intermediate spacer between the sheet 20 and the slide support 22. The above recited members of the suspending closure member 17 are rigidly united, preferably by countersunk rivets 23.

To the transverse bar 19 is hinged a closure 24 which is provided with two parallel slots 25 and 26 for two sealing loops 27 and 28 rigidly fastened to the slide 14 and the frame member 18, respectively. On the under side of the closure 24, there is secured a seal supporting loop 29, preferably aligned with the slot 21. The box is sealed by passing a flexible strip of strong gummed tape 30 through the sealing loops 27 and 28, a suitable signature card 31 is secured to the tape 30, the free end of which is then moistened and pressed against the card 31 across which are written certifying signatures and, as a further precaution, a strip of transparent tape 32 may be secured over the signatures on the card 31.

My device is designed for suspension by two folding hangers 33, each having a hook 34 for engagement with the edge of an open drawer 35, or the like. Each hanger is mounted in two bearings 36 which are attached to the suspending closure member 17 and, when folded, the hooks 34 may be reciprocated in the bearings 36 for retention under a retaining clip 37. As is clearly shown in Fig. 1, when the slidable hook means 33—34 are in the position in which they lie flat against the frame 18 and are being moved under the keeper 37, the resilient arms 33 thereof flex to slide over the raised portion 24a of the hinged cover 24 and drop therebehind, as the portions 34 approach their maximum projection under the keeper. The raised portion 24a thus serves to retain the slidable hook means 33—34 in the keeper 37 until forcibly withdrawn therefrom.

My "ballot box" may be readily transported in an ordinary brief case, even though the pouch provides ample room for receiving a large number of ballots. The provision for sealing a closed ballot box also provides protection against tampering equal to that of a ballot box having a rigid ballot receiving receptacle.

In operation, my device may be supported on a desk drawer, or the like, with the closure 24 turned back to expose the slot 21 and the seal supporting loop 29, by means of the suspending hangers 33. At the close of the balloting period, the closure 24 is turned to the slot sealing position, a gummed tape 30 of a signature card 31

is passed through the sealing loops 27 and 28, then moistened and pressed against the card 31. The signatures of the judges of election are written across the card 31 and the tape 30 after which the signatures may be protected by a piece of transparent adhesive tape 32. With my novel ballot receptacle, a single supporting frame may be used with a plurality of detachable pouches bearing different stencil markings. Worn out or defective pouches may also be replaced with a minimum loss of time and a material saving in cost of replacement. The hook means 33, retained in keeper 37, holds cover 24 closed. Thus seal strip 30 is relieved of any strain of holding the cover 24 closed or holding the slide 14 in the frame.

Since many widely differing embodiments of this invention will occur to one skilled in this art, the invention is not limited to the specific embodiments illustrated and described, and changes and variations of the invention can be made without departing from the spirit and scope thereof.

What I claim is:

1. A collapsible ballot receptacle comprising an open mouthed flexible pouch having a stiff, flat, horizontally extending flange about its mouth; a slide having an opening for the passage of the pouch therethrough and having a marginal recess about said opening for removably receiving and supporting said flange; a slide receiving frame having grooves for slidably receiving said slide, said frame preventing removal of said pouch from said slide when in place therein, said frame having a ballot slot therethrough overlying the opening in the slide and the open mouth of the pouch when in place therein and having a cover plate hinged to said frame and in one position overlying and closing said ballot slot; said cover plate and slide being provided with interengaging means for holding said slide in said frame in the closed position of said cover, said frame further having slidably mounted thereon supporting hook means in one position extending beyond the frame to engage over a drawer edge or the like, and in another position thereof lying flat on said

frame and holding said hinged cover in closed position, and said frame comprising means for holding said slideable hook means in said last named position thereby holding said cover closed and said slide and pouch in the closed frame.

2. A collapsible ballot receptacle according to claim 1, in which the means for holding said slideable hook means in said last named position comprises a keeper under which the slideable hook means is slideable when flat on the frame, and a raised portion on the frame that a part of the slideable hook means resiliently slides over and drops behind in sliding into said keeper, said raised portion retaining said slideable hook means in said keeper until forcibly withdrawn therefrom.

3. A collapsible ballot receptacle according to claim 1 in which said interengaging means comprises an upstanding sealing loop carried by said slide and a slotted hasp carried by said cover and positioned to pass over said upstanding sealing loop in the closed position of said cover with the slide in place in the frame, and in which said frame further comprises a second sealing loop that in the closed position of the cover lies adjacent the portion of said slide carried loop projecting through said hasp slot, said loops providing for the passage of a sealing strip therethrough, and said hook means and the means for holding the same in the position in which the hook means holds the hinged cover closed, serving to relieve such sealing strip from the strain of holding the cover closed, while the hasp engagement with the slide loop relieves such sealing strip from the strain of holding the slide in position in the frame.

RUSSEL R. MILLER.
